CAR RETARDING APPARATUS

Application filed August 30, 1930. Serial No. 479,022.

This invention relates to car retarding apparatus of the kind adapted to be located adjacent to the track rails of a track over which the vehicle to be retarded travels and comprising brake bars or their equivalent adapted to be automatically brought into engagement with the wheels or other portions of the vehicle by electro-magnetic action, so as retardation of the vehicle is thus not only effected by frictional action but also due to the eddy currents generated by the movement of the wheels or other portions of the vehicle relative to the magnetic flux traversing the brake bars.

In order that this eddy current effect may be utilized economically to the greatest possible extent, it is evidently desirable that the path of the magnetic flux traversing the magnetic circuit including the brake bars should have as low a magnetic reluctance as possible so as to enable a maximum of magnetic flux to be generated for a given energizing winding and a given consumption of energizing current.

It is also desirable that the magnetic circuit above mentioned should remain continuous and efficient regardless of lateral displacement of the vehicle relative to the track rail during running and regardless of variations in the transverse width of the vehicle wheels or other portions of the vehicle engaged by the brake bars.

These and other desirable objects are attained by the improved construction of the invention which enables the brake bar to follow accurately and continuously any irregularities or displacements in the wheel or other part of the vehicle engaged by the brake bars without risk of jamming or impairing the magnetic conductivity of the circuit including the brake bars as will be hereinafter described.

The invention is illustrated by way of example in the accompanying drawings of which Figure 1 is a view in transverse sectional elevation of car retarding apparatus embodying one form of the invention. Figure 2 is a similar view on an enlarged scale of the upper portion of one side of the car retarding apparatus shown in Figure 1.

Figure 3 is a view in side elevation illustrating a modified construction, Figure 4 being a view similar to a portion of Figure 1 illustrating a still further modification.

Referring now first to the construction shown in Figures 1 and 2 the car retarding apparatus is shown as comprising horizontal laminated core members 1 on the opposed inner edges of which are mounted brake bars 2 located on each side of a track rail 26 along which one of the wheels of the vehicles to be retarded travels. The core members 1 are magnetically connected to a horizontal yoke 4 (located underneath the cross-tie on which the track rail 26 is supported) by means of vertical core members 3 each of which as best shown in Figure 2 consists of a plurality of relatively thin metal plates stacked together side by side with one another. The upper and lower edges of the plates 3 are preferably bevelled or rounded as indicated at 13 in Figure 2 and the outermost plate 14 is of greater thickness than the other plates of the stack. The upper and lower edges of the plate 14 are however reduced in thickness and bevelled or rounded as shown in Figure 2 so as to conform to the edges of the remaining plates.

The energizing coil of the apparatus is indicated at 25 as surrounding the horizontal yoke 4, this coil being preferably enclosed as shown in Figure 1 in a sheet metal casing the seams of which are welded so as to prevent the entrance of moisture or dust. This casing is preferably filled with insulating material of any suitable character.

The core members 1 are mechanically connected to the core members 3 by hinges, the core members 3 being similarly mechanically connected to the yoke 4. One form of hinge connection which may be employed is shown on the left-hand side of Figure 1 and comprises a hinge of which the upper hinge plate 5 is secured to the outer vertical edge of the core member 1. The lower hinge plate 7 lies against the outer face of the outermost core plate of the core member 3 but is not however attached thereto.

The lower hinge plate 6 of another hinge is secured to the outer vertical end or face of

the yoke 4 the upper hinge plate 8 lying against the outermost core plate of the core member 3 below the hinge plate 7 without being attached to the core plate.

5 The free edges of the hinge plates 7, 8 are bent outwards as shown, these edges being engaged by a spring member 9 of substantially semi-circular cross-sectional form.

10 The member 3 consists, as already stated, of a stack of relatively thin plates, the lower edges of which rest on the member 4 and the upper edges of which support the member 1. The stack of plates forming the member 3 is confined at its upper end between the hinge 5-7 and a projection 17 on the lower surface of member 1. The stack of plates forming member 3 is confined at its lower end between the hinge 6-8 and a shoulder 18 forming one end of a shallow recess in the 20 upper surface of the yoke member 4.

There is, therefore, no provision for sliding movement of the member 1 relative to the member 3, or of the member 3 relative to the member 4. The movement of the member 1 towards and away from the track rail 26 is effected by the tilting action of the plates of which the member 3 is composed. Each individual plate is in contact at its upper end with the member 1 and at its lower end with the member 4. The points of contact of the ends of these plates constitute the pivots or rocking points permitting the movement of each plate about its lower end as a center. As a result of this arrangement, it will be seen that the brake bar 2 and member 1 can be moved toward and away from the track rail and that during such movement the stack of plates forming member 3 constitutes a composite hinged element connecting the members 1 and 4. The movement of the member 1 toward and away from the track rail does not take place along a truly horizontal line, but, on the contrary, its path is actually a circular arc having a radius dependent upon the vertical height of the plates of which the member 3 is composed. It will be apparent that the resilient connections between the hinge members 7 and 8 do not in any way oppose the swinging movement of the member 3, since the distance between the pivotal points of the hinges is not altered by the tilting of the stack of plates of which member 3 is composed.

55 In operation it will be apparent that when the energizing coil 25 of the apparatus is supplied with current, magnetic flux is caused to traverse the yoke 4, core members 3, core members 1, brake bars 2 and the wheel of a vehicle passing along the track rail 26 between the brake bars 2. The brake bars 2 are thus caused to engage frictionally with the vehicle wheel and the rotation of the wheel is retarded due to the frictional engagement above mentioned and to the eddy currents generated in the wheel.

It will be appreciated that the horizontal movement of the brake bars 2 towards one another to engage with the sides of the wheel under the magnetic action is permitted by the special construction of the 70 core members 3 above described and owing to the provision of the hinges 5, 7 and 6, 8 and to the resilient connection between these hinges constituted by the spring member 9, the horizontal inward movement of the 75 brake bars 2 can occur without any risk of jamming of the stacked plates of the core members 3, this movement being also facilitated by the rounded or beveled edges of these core plates. During the inward and outward movements of the brake bars 2 the core members 1 can thus seat themselves evenly and uniformly upon the upper edges of the core-plates 3 due to the resilient connection between the hinges 5, 7 and 6, 8 and similarly the lower edges of the core plates 3 are for all positions of the brake bars 2, 80 evenly and uniformly seated on the yoke 4.

85 An alternative arrangement for resiliently connecting the hinge plates 7 and 8 is illustrated at the right hand side of Figure 1 and in Figure 2. In this construction the lower end of the hinge plate 7 and the upper end of the hinge plate 8 are each bent over at right angles and are resiliently connected together by a bolt 10 and a nut 11, springs 12 being interposed between the end of the hinge plate 8 and the head of the bolt 10 and between the end of the hinge plate 7 and the nut 11 as shown in Figures 1 and 2.

90 In another form of construction shown in Figure 3, two hinges each composed of hinge plates 5, 7 respectively are provided, the hinge plates 5 being secured to the outer face of the core member 1. The yoke 4 is provided with a single hinge comprising hinge plates 6, 8 of which the hinge plate 6 is secured to the outer end or face of the yoke 4. Leaf springs 15 are interposed between the bent-over ends of the hinge plates 7, 8, the ends of these leaf springs engaging with the hinge plates 7 and the middle of the leaf springs 15 engaging with the hinge plate 8.

95 In the still further form of construction shown in Figure 4 the core member 1 and the yoke 4 are resiliently connected together by a hinge device comprising an upper hinge plate 5 secured to the outer face of the core member 1, a lower hinge plate 6 secured to the outer face of the yoke 4 and an intermediate curved resilient member 16 connected to the lower edge of the hinge plate 5 and to the upper edge of the hinge plate 6 by articulated hinge joints.

100 In all the constructions illustrated and described it will be seen that the core members 3 are resiliently clamped between the core members 1 and the yoke 4 and the core members 1 carrying with them the brake 130

bars 2 are thus rendered capable of inward and outward movement towards and away from the track rail 26 without impairing the magnetic circuit of the apparatus.

Although only certain forms of apparatus embodying the invention have been described and illustrated by way of example, it will be understood that various modifications may be made within the scope of the appended claims without exceeding the ambit of the invention.

Having now described our invention, what we claim as new and desire to secure by Letters Patent is:—

1. In car retarding apparatus the combination of a stationary yoke, a relatively movable core member carrying a brake bar, means for magnetically connecting said yoke and said core member and resilient means including a hinge for mechanically connecting said yoke to said core member.

2. In car retarding apparatus the combination of a stationary yoke, a relatively movable core member carrying a brake bar, means interposed between said yoke and said core member for transmitting magnetic flux and means including a hinge for resiliently connecting said yoke to said core member.

3. In car retarding apparatus, the combination of a stationary yoke, a relatively movable core member carrying a brake bar, means for transmitting magnetic flux interposed between said core member and said yoke and a resilient hinged connection between said core member and said yoke.

4. In car retarding apparatus the combination of a stationary yoke, a substantially horizontal core member, a substantially horizontal brake bar carried by said member, a stack of substantially vertical plates composed of magnetic material interposed between said core member and said yoke and resilient means including a hinge for maintaining said stack of plates in magnetic contact with said horizontal core member and with said yoke.

5. In car retarding apparatus the combination of a stationary yoke, an upper core member carrying a brake bar, a plurality of relatively thin metal plates having upper and lower rounded edges and engaging at said edges with said core member and with said yoke respectively and resilient means for maintaining said engagement.

6. In car retarding apparatus the combination of a stationary yoke, an upper core member carrying a brake bar, a plurality of relatively thin metal plates having upper and lower rounded edges engaging at said edges with said core member and with said yoke respectively, an outer relatively thick metal plate having upper and lower rounded edges of the same form as that of the edges of said thin plates, said outer member also engaging with said core member and with said

yoke and resilient means for maintaining said engagement of all of said plates.

7. In car retarding apparatus the combination of a track rail over which a wheel of a vehicle to be retarded travels, a brake bar on each side of said wheel, a substantially horizontal core member secured to each of said brake bars, a substantially horizontal stationary yoke extending transversely below said track rail on each side thereof, a stack of substantially vertical thin plates of magnetizable material interposed between each of said core members and said yoke, an upper hinge having an upper hinge plate secured to one of said cores, a lower hinge having a lower hinge plate secured to said yoke, a lower hinge plate for said upper hinge, an upper hinge plate for said lower hinge and means for resiliently connecting the lower and upper hinge plates of said upper and lower hinges respectively.

In testimony whereof we have hereunto set our hands.

WOLFGANG BASELER.
AUGUST MEYER.
